UNITED STATES PATENT OFFICE

JOHN G. STAMM, OF EAST CLEVELAND, OHIO

HYDRAULIC SUCTION DEVICE

Application filed April 23, 1928. Serial No. 272,235.

My invention relates to improvements in hydraulic induction devices.

An object of my invention is to provide for the efficient induction of air by a jet of liquid, in such an improved manner that the jet will not be disrupted by the induced flow of air as is the case in certain prior constructions where a swirling effect upon the air is created in the induction chamber, with consequent disruption of the jet and a considerable resultant loss of efficiency in induction.

Another object of my invention is to provide an improved suction cleaner that may take up water as well as dirt without injury thereto.

Another object of my invention is to provide an improved suction device which contains a minimum number of parts, that is inexpensive to manufacture, inexpensive to operate and which requires little or no attention after installation.

Another object of my invention is to provide a device of the class described that may be used in conjunction with any of the various types of high pressure pumps.

Other objects of my invention and the invention itself will become better understood by reference to the following description of an embodiment of my invention illustrated in the attached drawings forming a part of this specification.

Referring to the drawings:

Fig. 1 is a vertical medial sectional view of an embodiment of my invention;

Fig. 2 is a vertical medial sectional view taken at right angles to that of Fig. 1;

Fig. 3 is a plan view of the device of Fig. 1;

Fig. 4 is a fragmentary sectional view of an air inlet; and

Fig. 5 is a diagrammatical view of one of the devices of my invention as connected for operation.

Referring to the figures of the drawings wherein like parts are designated by like reference characters, at 1, Fig. 1, I have provided a hollow elliptical casing having an upper chamber 2, and a threaded orifice 3 adapted to receive a conduit. The upper chamber

2 diverges at 4 to form a pair of passages 5 and 6, which surround a downwardly extending pear-shaped center 7 and converge into a chamber 8 from the two separate sides. The center 7 is formed with a sharp dividing point where the passages diverge and at the lower part a blunt plane 9 is formed having a pair of modified ridges 10 substantially triangular in shape extending at nearly right angles thereto with their thickest portions at the edges of the opposite sides of the plane and gradually tapering outward towards the lower point 11 as it nears the exhaust end, finally merging with the walls of the casing. The extremity of the exhaust chamber is threaded at 13 to provide means for attaching an exhaust conduit substantially as illustrated in Fig. 5.

The pear-shaped center 7 which is surrounded on two opposite sides by the passages 5 and 6 is provided with a chamber 14 disposed in the lower portion thereof. A pair of canals 15 and 16 open into the chamber 14 and are threaded to receive therein a pair of conduits not shown. The bottom of the chamber 14 connects with the upper part of the exhaust chamber 8 by a threaded canal 17 into which is screwed a jet or nozzle 18. A suitable gasket 19 is interposed between a shoulder 20 of the jet and the end of an enlarged portion of the canal 17 making a fluid tight connection therebetween. The jet is provided with a cylindrical duct 21 extending longitudinally therethrough and opening into the chamber 8 through the planar surface 9 in substantially axial alignment with the exhaust chamber 8.

The upper end of the casing is provided with a pair of oppositely disposed threaded bores 42 and 43 adapted to receive conduits not shown. When a source of water is applied thereto, the side of the casing may be readily cleaned.

A source of fluid under pressure is conducted by conduits to the two canals 15 and 16 and is forced downward through the orifice 21 into and through the chamber 8. The high velocity with which the fluid flows induces a current of air to flow through the

upper suction inlet downward through the branch passages 5 and 6 and out with the stream of water at 12.

The branching of the passages 5 and 6 causes the air stream to engage the water stream on both sides with equalized pressure preventing the eddying currents that are usually set up in devices of this character and eliminating back siphoning of the water. 10 This is further facilitated by the stream line ridge 10 located on the opposite sides of the air jet. The flat planular character of the housing and the fact that the jet is so formed that no hollow spaces or air pockets are in 15 back of the jet, closely adjacent to it, also tends to prevent the gathering of globules of water which would impair the efficiency of the device.

As best shown in Fig. 4 I have shown a 20 modified form of upper intake 22' which is substantially L-shaped, although the operation is the same as in the device having the intake opening vertically.

The device may be constructed of a single 25 casting of cast iron, malleable iron, brass or any metal which may be rendered rust resisting. I preferably drill the canal of the jet 18 by using suitable jigs so that the canal extending through the jet is in axial alignment with the chamber 8. The intake and 30 exhaust ends of the device may be hexagonal in shape to receive a wrench for installation purposes.

In Fig. 5 I have illustrated diagrammatically one system of connecting the device of 35 my invention, wherein the source of fluid power comprises a motor 30 and a rotary pump 31 connected by conduits 32 to the device, and having a shut-off valve 33 interposed in the 40 conduit. An exhaust pipe 34 is connected to the lower end of the casing and may discharge to the sewer. I have shown a flexible hose 35 connected to the air intake which is provided with a nozzle 36 which may be any 45 of the various types. I find, that with the device connected as shown, that with pressure of 300 pounds of water, it is possible to displace approximately 300 cubic feet of air per minute, which creates a very efficient suction 50 device capable of sucking up water, dirt, or the like which ordinary suction devices cannot handle. This is especially to be desired around automobile washing racks where it 55 may be used in connection with high pressure washing systems.

The size of the canal in the jet to be used 60 may be varied by interchangeable jets which are screwed into the casing by a suitable spanner wrench which may be inserted in notches 23 in the large end of the jet.

Having thus described my invention in a 65 preferred embodiment, I am aware that numerous and extensive departures may be made from the embodiment herein illustrat-

ed and described but without departing from the spirit of my invention.

I claim:

1. In an air suction device, a hollow casing 70 provided with a water conduit construction therein, an air-receiving passageway, and a discharge passageway for mixed air and water, the conduit construction communicating with the outside of the casing whereby water may be conducted thereto and terminating inwardly of the casing in a substantially planular surface disposed at substantially right angles to the direction of flow of air through the casing from the air-receiving 75 passageway to the discharge passageway, a removable nozzle piece in the conduit construction provided with a minute duct having an orifice disposed in said planular surface, whereby a jet of water emerging from the orifice impinges at right angles upon the air in the casing in contact with said surface and whereby air in motion toward said emerging water jet moves at right angles to said jet and into contact therewith, the discharge passageway being of smaller cross- 80 sectional area than the air-receiving passageway, the discharge passageway being longitudinally spaced from and axially disposed relative to the said orifice and the casing being provided with lateral walls converging toward the discharge passageway from the 85 orifice.

2. In an air suction device, a hollow casing 90 provided with a water conduit construction 100 therein, an air-receiving passageway, and a discharge passageway for mixed air and water, the conduit construction communicating with the outside of the casing whereby water may be conducted thereto and terminating inwardly of the casing in a substantially planular surface disposed at substantially right angles to the direction of flow of air through the casing from the air-receiving 105 passageway to the discharge passageway, a removable nozzle piece in the conduit construction provided with a minute duct having an orifice disposed in said planular surface, whereby a jet of water emerging from the orifice impinges at right angles upon the air in the casing in contact with said surface and whereby air in motion toward said emerging water jet moves at right angles to said jet and into contact therewith, the discharge 110 passageway being of smaller cross-sectional area than the air-receiving passageway.

3. In an air suction device, a walled casing, 115 provided with a discharge passageway, casing walls converging toward the discharge passageway, an air inlet passageway in the casing wall, a water conduit construction disposed generally intermediately of the two passageways, the conduit construction communicating with the exterior of the casing whereby water may be conducted thereto and terminating inwardly of the casing in a rela- 120 125 130

tively small discharge duct, the conduit construction being provided with a planular face disposed substantially at right angles to a central axis of the discharge passageway 5 and the duct terminating in an orifice disposed substantially symmetrically centrally of the planular face, the duct being coaxial with said central axis, the parts being so arranged that air within the casing and in contact with said planular surface may be impinged upon at said surface by said jet at right angles to the air at said surface, and so that air in motion through the casing from the inlet passageway to the outlet passageway 15 may move transversely over said planular face at right angles to said jet and into engagement with the jet.

In testimony whereof I hereunto affix my signature this 20th day of April, 1928.

JOHN G. STAMM.
